UNITED STATES PATENT OFFICE.

FRANK J. GILROY, OF BUFFALO, NEW YORK.

DEVICE FOR SECURING CAR DOORS.

Application filed August 29, 1924. Serial No. 735,005.

This invention seeks to avoid robbery of railway cars by unauthorized opening thereof, it being well known to all railway men that great sums are lost annually through such opening, and for that reason much valuable freight is carried in cars provided in one way or another with means intended to minimize the loss.

Certain persons obtain low grade employment with railways and with the real object of opening and robbing cars, usually under pretense of slight repairs or adjustments, working from the ground without ladders to excite suspicion and taking care to avoid indisputable attempts at robbery.

In the accompanying drawings:

Figure 1 is a side elevation of a portion of a car door and adjacent parts of the car wall.

Fig. 2 is a view, partly in section, showing a door post and one of the air-brake cylinders, with a pipe from the brake system, passing upward within the car wall.

Fig. 3 is a view partly in section, through a keeper bracket.

Fig. 4 is a horizontal section of a portion of a door and adjacent car wall, at the latching devices.

Fig. 5 is a section on the line 5--5, of Figure 4, passing through the door post and latching devices.

Fig. 6 is a view looking from the right hand in Fig. 5.

Fig. 7 is a horizontal section of a portion of a fully open door and some adjacent parts.

Fig. 8 is a view of a modification showing a metal attachment analogous to a device of Fig. 7 but adapted to be riveted to a metal door.

In these figures, A represents a portion of a car wall and B one marginal portion of an adjacent car door. C represents a car floor, D the upper belt rail, E a door post, F the outer board sheathing of the car, G the corresponding inner boards, and H the door post past which the car moves in opening.

The latching is by means of a catch-bar I centrally pivoted on a bolt J passing through the post E. The bar's nonengaging end portion passes loosely through a vertically moveable member K fixed to a piston rod L, connected to a piston L' working in a closed cylinder M and normally held down by a helical spring M'. A valved, compressed-air pipe N enters the cylinder below the piston. This pipe comes from any convenient com-

pressed air conduit of the air-brake system, e. g., the train pipe or an air-brake cylinder N', and passes upward through the bottom of the car and thence, in the space between the boards F and G, to a point above the upper belt rail D where, as above stated, it enters the cylinder M, below the piston L'.

The end portion of the lever I and the upper end of the piston rod, or member K, are enclosed by a casing O integral with the cylinder but having one side wall O' riveted in assembling to the casing body by means of lugs O² and secured to the door post E by bolts P. Before the plate O' is fixed in place the casing O is fully open on one side so that the bar I and adjacent parts may be assembled with certainty.

When so assembled, riveting the side plate makes the interior of the casing inaccessible. The door post is recessed to receive a cup-like casing Q having a lower inclined wall Q' provided with a central lever-receiving depression Q² directly below the lever I. The end portion of the lever I has a lateral offset R and, above, a small hook R' which engages a lip R² on a rigid cross-bar R³ carried by the casing Q.

The lever I is also provided with an integral upwardly extending and terminally deflected guard "Z" which serves to protect the latching mechanism from wilful injury when the door is open. This guard Z is immediately in front of the fixed stop Y, and when in latching position the free end of this guard projects into a recess in the door post as shown in Fig. 5. In order that the spring M' may in no case swing the bar I too far so that the cross-bar R³ cannot ride over the inclined face of the bar's terminal portion and swing the bar, a fixed stop Y is provided.

The post is provided with a long vertical flanged member S, fixed to the post, covering the bolts J and furnishing a channel S' into which shuts the margin of the door, this latter margin being protected by a strip S² having a marginal web S³ barring the entrance of any strong tool by which the strip S might be torn off.

The door has an outer horizontal metal strip T and on the inner face of this margin of the door is a heavy plate T' integral with a heavy, irregular, projecting keeper T².

When the inclined lower face of the cross-bar R³ moves to closed position, with the door, it rides over the inclined end of the bar I, depressing the same while compressing the

spring **M'**, and allowing the keeper to engage the bar **I** in such manner that it can be disengaged only by rising of the piston, that is by air pressure below the latter.

- 5 Bolts **V** pass through the door and the plates **T**, **T'**, the bolts being provided with annular shoulders to receive the plate **T'** and with nuts sunk in depressions in the latter, so that when the door passes to fully open 10 position, the nuts may freely pass the post **H**, which is recessed to receive the keeper, as shown in Fig. 7. When an all metal door is used, the plate **T'** is omitted and a keeper **W**, Fig. 8, is riveted at **W'** directly to the 15 door. The keeper **T²** of the main form is provided with a member **X** which when the door is closed covers the end of the bar **I** and prevents it from being depressed by one within the car.
- 20 It is to be noted that the bolts **V** have heads which cannot be engaged for rotating them, and that even if the heads be cut off by one outside the car, they still hold the plate **T'**. It is also true that opening or closing the air 25 valve will be without effect in the absence of emergency application of the brake, as is the case with other related devices.

It is also of importance that the latching devices are so far above the ground that they 30 cannot readily be reached without a ladder or other devices for which the workman who tampers with similar locks has no legitimate use, there being no reason for his acting at such height for any proper purpose. Further, one inside the latched car cannot manually depress the lever and open the car for escape. It follows that even if a person is 35 well advised of the specific construction, it is practically impossible for him to open the 40 car through tampering with its fastenings.

The hook **R'** of the keeper-engaging end of the bar **I** and the lip **R** which it engages are very important, for without them it is possible to use a thin wedge gently urging the 45 door to open, and then by light hammering on the lower end or bend of the pipe **N**, the lever will be slightly tilted and frictionally held against return. Repeated blows may thus progressively depress the engaging end 50 of the bar until the door is released. When the hook and lip are present, the application of door-opening force, at once engages the hook and lip and such tilting of the bar or lever is prevented.

55 What I claim is:

1. The combination with a vehicle, of a pivoted door holding latch lying inside the outer sheathing of the vehicle above the load line, of a spring normally holding said latch 60 in latching position, a keeper provided with means for interlocking with said lever when moved in an opening direction while said lever is maintained in latching position and a reciprocating lever releasing means adapt- 65 ed for operation only by the sudden supply

of a relatively large volume of compressed air.

2. The combination with a door holding latch lying within a car wall above the load line of a keeper carried by a car door for 70 engaging the latch provided with a guard which when engaged with said latch completes the inaccessibility of the fastenings from within, or without the car, said fastenings being releasable only by a reciprocating 75 piston adapted for operation by the sudden supply of a relatively large volume of compressed air.

3. The combination with an inaccessible latch for holding a car door closed, of means 80 whereby the latch may be released by compressed air from a locomotive or the like, said latch and keeper being provided with a rearwardly open recess and a rearwardly extending hook for interlocking said latch and 85 its keeper whereby releasing is prevented by opening force applied to the door.

4. The combination with a railway car having a door front recessed above the load line to receive a swinging latch and a door-carried 90 keeper provided with an integral guard to engage the latch and render its engaging end portion inaccessible, said latch being disengaged only by a large volume of highly compressed air supplied from and controlled by 95 devices of a locomotive or a like distant source.

5. The combination with a car having the usual door-opening posts, of latch devices carried in a recess in one post, a wood door 100 provided with metal plates bolted to its opposite faces in the horizontal plane of said recess, a keeper integral with the inner of said plates and projecting when the door is open into a recess in the face of the post past 105 which the door moves in opening, said inner plate and the bolts which secure it being sunk in the door so that the latter may slide closely alongside the post.

6. The combination with a railway car having a sliding door, of a pneumatically released latch having a lever concealing casting, a keeper having an integral protecting shield for the engaging members of said latch, said engaging members having interlocking portions which engage when opening force is applied to the door. 110

7. The combination with a vehicle provided with a door, of a resiliently held pivoted latching lever provided with an integral guard and with means for interlocking with a keeper, a keeper provided with co-operating interlocking means and with a guard for said lever, and means for unlatching said door only by the sudden supply of a 115 large volume of compressed air.

In testimony whereof I hereunto affix my signature.
